UNITED STATES PATENT OFFICE.

GEORGE H. STERLING, OF MINNEAPOLIS, MINNESOTA.

PADLOCK.

Application filed March 26, 1923. Serial No. 627,657.

To all whom it may concern:

Be it known that I, GEORGE H. STERLING, a citizen of the United States, residing at Minneapolis, in the county of Hennepin and 5 State of Minnesota, have invented certain new and useful Improvements in Padlocks; and I do hereby declare the following to be a full, clear, and exact description of the invention, such as will enable others skilled 10 in the art to which it appertains to make and use the same.

This invention relates to a lock and particularly to a type of lock similar to the well known padlock type.

15 It is an object of this invention to provide a lock of extremely simple form having a bow or locking member forming a substantially closed figure but having an open space between the ends thereof.

20 It is a further object of the invention to provide such a lock which, with the exception of the bow or locking member, is formed of a sheet of plate material.

25 It is still another object of the invention to provide a lock having simple and efficient means therein requiring a certain key formation, which means can be easily changed for various locks to require different key formations.

30 It is still a further object of the invention to provide a lock comprising a casing in one end of which the bow member is rotatable, which casing has therein a resilient means disposed in the opening of the bow member to lock the same against rotation, which 35 resilient means is movable by a key to release said bow member.

These and other objects and advantages of the invention will be fully set forth from 40 the following description made in connection with the accompanying drawings in which like reference characters refer to the same parts throughout the different views, and in which,

45 Fig. 1 is a perspective view of the lock;

Fig. 2 is a plan view thereof showing the casing in horizontal section;

50 Fig. 3 is a vertical section of the lock taken on the line 3—3 of Fig. 2, shown on an enlarged scale and showing the key in one position in the lock;

Fig. 4 is a view similar to Fig. 3 showing the key and key operating parts in different position;

55 Fig. 5 is a vertical section taken on the line 5—5 of Fig. 3;

Fig. 6 is a vertical section taken on the line 6—6 of Fig. 3;

Fig. 7 is a vertical section taken on the line 7—7 of Fig. 4;

Fig. 8 is a vertical section taken on the line 8—8 of Fig. 4;

Fig. 9 is a perspective view of the locking plate used;

Fig. 10 is a perspective view of a frame member used in the lock;

Fig. 11 is a perspective view showing a plurality of plates mounted in the frame member shown in Fig. 10;

Fig. 12 is a perspective view of a key stop plate used;

Figs. 13 to 15 are views in side elevation of the plate shown in Fig. 9 showing different forms of the same, a portion of the plate being shown in section in Fig. 15;

Fig. 16 and 17 are views in side elevation of the frame member shown in Fig. 10, said views showing different arrangements of slots in said member;

Fig. 18 is a perspective view of a key used;

Fig. 19 is a view in end elevation of the key plate;

Fig. 20 is a perspective view showing a modified form of the plates shown in Fig. 11;

Fig. 21 is a view in front elevation showing a modified form of key plate and

Fig. 22 is a view in side elevation of the partial assembly of the parts.

Referring to the drawings, the lock comprises a casing 1 having a portion at one end of substantially rectangular shape, which portion has projecting in opposite directions therefrom curved arms 2, said arms being illustrated as forming part of a circle. The

55 said casing is made from two sections of sheet metal which are pressed into the desired shape and one of which has a side flange 3 over which is turned and tightly pressed the flange or edge 4 of the other section. The sections of the casing are pressed together with great pressure and an exceedingly strong casing is thus made. The arms 2 of the casing are formed to provide a curved passage therethrough adapted to 105 accommodate a bow or locking member 5.

The member 5 is formed to constitute substantially a closed figure, the ends of which, however, are separated a short distance, thus forming a gap and in the embodiment of the

105 invention illustrated, said member is shown of substantially circular form and of cylind-

drical cross section, although it is obvious that other forms of bow members may be used. The casing 1 at the end opposite the arms 2 is provided with a circular aperture, 5 and a key plate 6 having therein a key slot 7 is disposed in said aperture and pressed therein in firm position. A resilient member 8 formed of a rectangular plate bent into substantially triangular form is provided 10 and disposed in the casing 1 with its short side against the member 6 and with its end portions extending to the other end of the casing 1 and being disposed in the gap between the ends of the member 5. A T-shaped 15 plate 9 is provided and extends transversely across the casing 1, the member 8 having slots 10 through its sides through which the opposite upper and lower arms of plate 9 extend. The member 8 is provided with 20 pressed-in folds or projections 11 extending toward each other a short distance from the slot 10. It will be noted that the short side of the member 8 at the end thereof is slightly curved inwardly. The member is made with 25 its curved portion so that it has a tendency to center itself in the casing. A yoke member 12 formed of a rectangular plate bent into bail or U-shape form with right angle bends is disposed in the casing 1, and has 30 its end portion substantially in contact with the end portion of member 8 and disposed in the latter member. The side portions of the member 12, however, extend at the sides of the member 8 in contact with the 35 sides of the casing. The end portion of the member 12 is provided with a key receiving opening 13 having horizontal slots at the opposite sides thereof and the side portions of the member 12 are provided with a plurality of spaced vertical slots 14 of different 40 lengths. A plurality of plates 15 of rectangular form provided with a key receiving openings 16 with horizontal slots extending therefrom at opposite sides are arranged to be disposed in the slots 14 and are 45 of the proper widths to fit therein. The casing 1 is wider at its end opposite the arms 2 than it is adjacent the arms 2 as clearly shown in Fig. 1, and the wider portion is 50 provided with upwardly curved sides 1^a, as shown in Figs. 5 to 8. It will be noted that the sides of the member 12 will be disposed in this wider portion and will extend above and below the member 8 and will be prevented 55 from endwise movement in the casing by a shouldered portion 1^b thereof. The member 12 is thus firmly held in position in the casing 1 and furthermore cannot move past the shoulder 1^b so as to come into contact with the member 5 or bind thereagainst. The member 12 is also firmly held in transverse position so that the same cannot shift and bind against the member 8. When the 60 lock is assembled the plates 15 will be held in position and prevented from endwise 65

movement by engagement with the sides of the casing 1.

A key member 17 illustrated in Fig. 18 is used with the lock and this member is shown as provided with a short narrow 70 tongue 18 at one end thereof and with a portion 19 adjacent the tongue of considerable length and is further provided inwardly from the portion 19 with a plurality of slots 20 forming short tongues or projections therebetween. The lock is normally in locking position and the sides of the member 8 tend to assume the position shown in Figs. 3 and 9, in which position said sides have their end portions disposed between the ends of the member 5 so that said member cannot be rotated in the casing 2. To release the member 5 and unlock the lock, the key 17 is inserted through the key opening 7 and the openings 13 and 16 in the members 6, 12 and 15, respectively. The key will be limited in this inserting movement by the front end of the portion 19 contacting with plate 9 and when the proper key is used, the slots 20 will be alined with the plates 15 and with the end portion of the member 12. The key can thus be turned in the lock and when turned through ninety degrees, the portion 19 which is disposed between the projections 11 will force said projections apart and with them the sides of the member 8 so that the end portions of these sides are moved out of the gap in the member 5 and out of alinement with said member, as clearly shown in Fig. 4. There is now no resistance to the rotation of the member 5 and said member can be rotated to bring the gap therein outside of the casing 1 when the lock can be removed from the staple or other member engaged and disposed in the bolt 5.

In Figs. 13 to 15, different forms of the member 8 are shown in which the projections 11 are located at different distances from the slots 10 which receive the plate 9. It will thus be seen that by merely changing the location of the members 11, locks requiring different keys will be formed. In Figs. 16 and 17, the members 12 are illustrated in which the slots 14 are arranged in different positions longitudinally of said member. It will thus also be seen that by changing the location of these slots, and hence, the location of the plates 15, that locks requiring different keys will be formed since the slots in the key must always aline with the plates 15.

In Fig. 22, the member 8 is shown with the projections 11 still farther removed from the plate 9 and said projections are so disposed that one or more of the plates 15 will be disposed between the projections and the plate 9. By varying the position of the projections 11 so that in different locks they will be engaged by different portions

of the key, the use of a master key for the locks is prevented. If a master key is made with all of the tongues between the notches 20 eliminated, in such a lock as shown in 5 Fig. 22, or in any lock where the projections 11 are not operated by the portion 19, such a key would fail to open the lock. If an attempt were made to make a master key with a long tongue or portion 19 thereon so 10 as to reach the projections 11 and one or more plates 15 are disposed between the projections 11 and plate 9, then such key will not turn in the lock. By using one or more of the plates 15 therefore and varying 15 the position of the projections 11 in relation to these plates locks requiring different keys are formed and it is impossible for anyone to construct a master key which will open all of said locks. Of course, it is possible 20 to construct a key which will open some one lock if the structure of the lock is known but such structure is not generally known to a person attempting to open the lock without the proper right to do so.

25 In Fig. 20, plates 21 are illustrated, which plates may be used instead of the plates 15 and said plates have openings 22 therein for receiving the key, which openings, however, are in the form of quadrants of a circle and have the straight sides 23. With these plates the key can only be turned in one direction to unlock and lock and a stop is formed by the side 23 for the key. In the form of plate 30 illustrated as 15 the key can be turned either way and will stand in position normal to the sides of the slots in the openings 16 when the lock is unlocked.

35 In Fig. 21, a key plate 24 is shown having therein a curved key slot 25 which will 40 require a key of similar shape.

45 From the above description it is seen that applicant has provided a very simple and efficient lock requiring an individual key. The lock, as stated, is made of simple plate 50 material and can be very easily and inexpensively produced. At the same time, the lock is exceedingly strong and can only be opened by having the proper key. By providing the plurality of plates a great number of permutations in the arrangement can be made so that an almost infinite number of locks requiring different keys can be made with but small change in the parts.

55 It will, of course, be understood that various changes may be made in the form, details, arrangement and proportions of the parts without departing from the scope of applicant's invention, which, generally stated, consists in the matter shown and described and set forth in the appended claims.

60 What is claimed is:

65 1. A lock comprising a casing having curved arms with a curved passage therethrough and a portion extending from said arms having substantially parallel sides, a

triangular member disposed in said portion having its free ends adapted to enter or be moved from said passage, a bail enclosing the base end of said triangular member and adapted to receive key plates, the opposite 70 sides of said portion of the casing being bent inwardly between the sides of said bail to hold the said bail in place and a bow member movable in said passage.

2. In a lock casing having diverging 75 curved arms with a semicircular passage therethrough and a substantially rectangular portion extending centrally from said arms, a key plate holder comprising a strip bent substantially at right angles into U- 80 shape disposed in said portion, the sides of said portion being bent inwardly to extend between the sides of said holder to hold the same in position.

3. The structure set forth in claim 2, said 85 rectangular portion having a shoulder contacting the ends of said holder to prevent longitudinal movement thereof.

4. A lock comprising a casing having a 90 key slot at one end, thereof, a locking member movable through the other end thereof and having an opening therein, a frame in said casing, a plurality of spaced plates supported in said frame having key receiving 95 slots therein and determining the key formation, a key stop plate and a resilient plate member bent into substantially triangular form having its sides portions adjacent their ends disposed in the opening of said locking member and having key engaging 100 projections whereby its sides may be separated and moved out of said opening to release said locking member.

5. A lock comprising a casing of substantially 105 rectangular form having curved arms extending in opposite directions at one end thereof, a passage through said arms and casing, a bow member forming a substantially closed figure but having spaced ends disposed in and rotatable in said passage, a 110 resilient plate member in said casing bent into substantially triangular form having its ends disposed between the ends of said bow member and adapted to be separated by the turning movement of a key to move out of said opening to release said bow member and a yoke member disposed in said casing embracing said plate member and contacting the walls of said casing.

6. The structure set forth in claim 5, and 115 a plurality of spaced plates in said yoke member having slots therein and determining the form of key to be used.

7. A lock comprising a casing having a 120 substantially rectangular chamber, a locking member having a gap therein movable across one end of said chamber, a resilient plate bent into substantially triangular form with its closed side adjacent the front 125 of said chamber and its end portions dis-

posed in said gap, a plate extending across said chamber adjacent the ends of said resilient plate to form a key stop, and a plurality of spaced plates extending across said chamber having key receiving slots therein and adapted to receive a key having slots therein alining with said plates so as to permit turning movement of said key, said resilient plate being adapted to be contacted by the key in its turning movement and have its sides moved out of said gap to release said locking member.

8. The structure set forth in claim 7, and a frame formed of a rectangular plate bent into U-shape having slots therein receiving said plurality of spaced plates and holding the same in position.

9. A lock comprising a sheet metal casing having a straight sided portion and substantially concentric arms diverging from one end thereof, said arms forming a curved passage for a bow member and said portion forming a shouldered chamber adapted to receive a bow engaging member and a key plate receiving member, said casing being formed of two sections divided along the central plane of said curved passage and provided with outwardly extending flanges at the inner and outer sides of said arms, the flanges on one of said sections being wider than and folded over the flanges of the other section into substantially parallel relation thereto whereby the bow-engaging member and key plate receiving member are retained in said casing.

10. A lock comprising a casing having a curved portion with a curved passage therethrough and a portion projecting therefrom, a bow member forming a substantially closed figure but with spaced ends movable in said passage, a resilient plate disposed in said last mentioned portion bent into substantially triangular form with its sides converging and having their end portions disposed between the ends of said bow member to prevent movement thereof and lock the same in position, said plate having an aperture in its base end portion adapted to receive a key extending longitudinally between said side portions to engage said side portions and move the same out of aline-

ment with said bow member and means extending transversely of said plate through which the key passes.

11. The structure set forth in claim 10, the sides of said plate having inwardly extending projections adapted to be engaged by the key to separate said side portions whereby by varying the location of said projections locks requiring different keys may be formed and the use of a master key prevented.

12. The structure set forth in claim 10, and an open-sided rectangular frame of plate material having its end extending across the end of said first mentioned plate and its side portions extending along the side portions of said first mentioned plate and substantially normal thereto, said casing having recesses therein in which the side portions of said rectangular member fit to prevent longitudinal movement thereof.

13. A lock comprising a casing having curved arms with a curved passage therethrough, a bow having an open portion slideable in said passage, said casing having a substantially triangular member therein with its base at the outer end of said casing and its free ends adapted to be disposed in said passage or to be moved to each side of the same, the base of said triangular member being curved inwardly.

14. In a lock, a sheet metal casing and a key plate member therein, of a three-sided rectangular formation, the walls of said casing being bent inwardly between the sides of said member and inwardly at the ends thereof to hold said member in place.

15. In a lock, a casing comprising a substantially rectangular portion having an outer end with an aperture therein and curved diverging arms extending from its other end, a key plate having a key slot therein and formed with a portion disposed in said aperture and also formed with a flange extending about the inner side of said aperture.

In testimony whereof I affix my signature.

GEORGE H. STERLING.
